UNITED STATES PATENT OFFICE.

REUBEN T. SITTERLEY, OF CARTHAGE, MISSOURI.

TIME AND INTEREST INDICATOR.

SPECIFICATION forming part of Letters Patent No. 322,757, dated July 21, 1885.

Application filed January 14, 1884. (Model.)

To all whom it may concern:

Be it known that I, REUBEN T. SITTERLEY, of Carthage, in the county of Jasper and State of Missouri, have invented a new and useful Improvement in Time and Interest Indicators, which improvement is fully set forth in the following specification and accompanying drawings, in which—

Figure 1 is a face view of my improved time and interest indicator. Fig. 2 is a diametrical section of the same. Fig. 3 is an enlarged view of a sector, showing the manner in which the indicator is used.

The object of my invention is to provide a calendar which computes the interest at any per cent. and for any portion of time. In addition to which the device indicates the number of days or weeks prior to or after a given time, as well as affords a ready means of ascertaining the day upon which the 1st of January of any year falls, or of any other day of the year, as will appear from the following description.

The device consists of a large disk, which is secured centrally to the spindle of a knob or handle on the under side of the disk. Upon this disk is placed a second one, smaller in diameter than the first, and adapted to be rotated on the spindle. A thin and flat straight-edge is also pivoted loosely on the spindle, and is designed to be turned around on the faces of the two disks above referred to. A third disk, smaller than the second, is then placed centrally on the spindle, and secured to it so that it will only rotate with the latter. A spur on the straight-edge or rule extends partly over the smallest disk, so as to indicate the figures on the radial lines thereon. The faces of the disks and rule are suitably lettered and figured to properly show by the aid of the rule the figures desired in any calculation, all of which will be now more fully explained. The largest disk, A, and the smallest disk, C, are rigidly secured to the spindle D. The middle disk, B, rotates freely on the spindle. The rule or straight-edge E is free to be turned around the said spindle, and one of its edges, E', is a true radial line from the axis of the spindle D. The rule is preferably placed between the disks C and B, although it may be between the disks A and B. As shown in this

instance, a spur, F, extends over the face of the smallest disk, C. The face of the disks have certain figures and letters thereon, which I will now explain, particular reference being had to Fig. 3, which is enlarged for clearly displaying the characters on the several disks and on the rule. The largest disk, A, has three hundred and sixty radial lines, G, forming spaces representing the three hundred and sixty days of the twelve interest-months of thirty days each. It also has a number of concentric lines, H, and there may be as many of these latter as desirable, so as to permit of placing thereon from one to twelve figures or more. The inner circle, I, on this disk has indicated on it the days from one to three hundred and sixty, inclusive, and the figures in the spaces formed between the radial lines G and concentric lines H indicate the interest.

It will be observed that the rule E has near its radial edge E' a series of figures from 1 to 8, which represent the dollars on which interest is to be calculated.

By referring to the smallest disk, C, it will be seen that the outer circular space, J, indicates the day of the week, the next column, K, the true time—that is, the day of the year—in contradistinction to the column I, which gives interest time. Column L numbers the days of the week successively, and column M gives the number of the week after or before a given time. The column M' gives the names of the week-days opposite the years in column N, while the last or inner column, N, gives the successive years. This will indicate on what day the year came in. For instance, referring to 1876, it will be found that "Sa" is in the next column, indicating that January 1st, 1876, fell on Saturday. By this means the day of the month of any week-day can also be found. The starting-point in column I, showing interest time, is one day ahead of the true or calendar time as given in column K. The middle disk, B, has three circular divisions, the outer division, O, having the interest-days of the month from 1 to 30, inclusive, while the inner division, P, has the true number of days which occur in each month. The name of the month is printed in the middle division, Q. Thus while both the interest and true days are given side by side, no conflict

can arise in computing the interest, or in finding the number of days, or in making any other calculation that is desired. Thus, for instance, should it be desired to find out how many days intervened between January 20 and March 24, the middle disk, B, would be moved to the position shown in Fig. 3, with the figure 24 of March in column P opposite figure 1 in column K nearest the rule E. The rule is then turned so as to rest over the figure 20 in column P of January, when the radial figure in column K will show the correct number, which is 63. The true number of interest-days, however, is sixty-four, as shown in column I, since both January and February must have thirty days, whereas by true time they have thirty-one and twenty-eight days, respectively, in ordinary years.

It will be noticed that the rule E has represented on it a series of figures from 10 to 400 radially, and from 10 to 50 concentrically. These figures show the interest-calculations for even years, and for convenience they are placed on the rule. Thus, as shown in Fig. 3, if the object is to find the interest of seven dollars at ten per cent. for one year and seventy-eight days, the first column on the rule E nearest the edge E' of the rule, 7, in the dollar column gives 70 cents as interest for one year, and then by placing the rule so that its edge E' shall be just to the left of 78 on the inner circular column, H, on the disk A the figures in the outer concentric row on this disk A which come nearest 7 give 15 cents for the 78 days.

While this drawing only shows calculations of interest on sums of five dollars and less, it will be obvious that the principle above clearly explained can be applied to any sums which can be entered on the rule E. In practice I design to make this adapted for \$1,000.

As shown in the drawings, the calculations are made on the basis of ten per centum per annum; but I do not confine myself to this per cent. I find it is much more convenient to compute the interest at this per cent. and then multiply the result so obtained by the per cent. desired, when, by striking off the right-hand figure of the product, the correct result is ascertained.

I am aware that interest and time calculating disks and pointers have been used before the within-described device, and I do not, broadly, claim such devices.

Having described my invention, I claim—

1. An interest and time calculating device consisting of the fixed disks A and C, the intermediate disk, B, and the movable rule E, having characters on them, as shown and described, in combination with the central spindle, substantially as specified.

2. The combination of the central spindle, D, the disks A and C fixed thereto, the disk B, and rule E movable thereon, and a spur, F, on rule E, all substantially as and for the purposes described.

3. A time and interest indicator comprising a disk, A, fixed on a spindle, D, and having radial lines representing twelve months of thirty days, concentric lines leaving space on which are figures representing dollars, and an inner circle having figures representing days from one to three hundred and sixty and interest time, and spaces indicating interest, a movable rule, E, having columns of figures representing dollars on which interest is to be calculated, a fixed disk, C, having an outer circular space indicating days of the week, a space indicating true time, a circular space indicating the number of days of the week, a space giving the number of the week after or before a given time, also a space giving the successive years, and a middle movable disk, B, having three circular divisions, the outer division, O, showing interest-days of the month, an inner division, P, showing true number of days in each month, and an intermediate division showing the names of the month, all as herein described and shown.

In testimony that I claim the foregoing I have hereunto set my hand, this 8th day of November, 1883, in the presence of witnesses.

REUBEN T. SITTERLEY.
